BRACELET OR SIMILAR ARTICLE

Michael Chernow, New York, N. Y.

Application January 24, 1950, Serial No. 7,453

Term of patent 14 years

(Cl. D45—4)

To all whom it may concern:

Be it known that I, Michael Chernow, a citizen of the United States and residing at New York, in the county of New York and State of New York, have invented a new, original, and ornamental Design for a Bracelet or Similar Article, of which the following is a specification, reference being had to the accompanying drawings, forming part thereof, and in which

Fig. 1 is a perspective view of the bracelet or similar article, showing my new design,

Fig. 2 is a fragmentary plan view thereof and, Fig. 3 is a fragmentary side elevation thereof.

This application is a continuation in part of copending application Serial No. D-149,682, filed November 17, 1948, now abandoned.

I claim:

The ornamental design for a bracelet or similar article, substantially as shown.

MICHAEL CHERNOW.
